WIRE FORMED KNITTING IMPLEMENT

Friedrich Max Clauss, Berkshire Heights, Pa.,
assignor to Textile Machine Works, Wyoming, Pa., a corporation of Pennsylvania

Application April 20, 1933, Serial No. 666,958

9 Claims. (Cl. 66—96)

This invention relates to articles which may be composed of, or formed from, wire, such, for example, as certain implements used in, or in conjunction with various types of knitting machines.

- 5 The present invention more particularly concerns the novel production of elements of the general type noted, which may include needles, welt hooks, lace and narrowing points, topping bar points or the quills of a transfer ring.
- 10 During the production of knitted fabrics, such as full fashioned hosiery of a plain, lace, or net type, it becomes necessary at times to transfer selected loops from one or a series of needles to another needle or series thereof in the same machine, as occasioned, for example, during the leg or foot fashioning process, or, in the effecting of a desired design; or to transfer stitches formed on the needles of one machine to the needles of another machine, as effected during the transfer 15 of the leg blank from a topping bar to the foot-forming machine, as required between the legging and footing operations.
- 15 In order to facilitate the shifting of loops in one machine, as above noted, one or more series 20 of transfer points are used, which cooperate with the needles in a manner to effect the desired result.

The transfer points used in combination or conjunction with straight knitting machines employed to produce full fashioned hosiery, are ordinarily manufactured from wire bent and swaged to the desired shape and form.

25 In the usual procedure, the wire, after being cut to desired length, has the needle-engaging 30 groove formed therein, following which the outer sides of the walls defining said groove are machined to the desired cross-sectional size and shape, after which the opposite ends of the wire 35 are bent and shaped to produce the desired foot and needle-engaging point respectively, to complete the transfer point.

40 The method of producing transfer points, according to the prior art, includes using wire of a size corresponding to the diameter of the shank 45 of the finished element. The customary manufacturing procedure entails the wasting of an appreciable amount of material, due to the fact that when the needle-engaging groove is formed the metal displaced thereby is added to and thereby thickens the body of the walls defining the groove, which consequently become more massive than is permissible or desired. This excess material in the walls must be reduced or entirely eliminated in order that the dimensional 50 characteristics of the finished implement will

conform to those specified for that particular gauge of transfer point which, according to the practice of the prior art necessitate the use of that particular gauge of wire, consequently the surplus metal is wasted.

5 In addition to the waste of material ordinarily associated with the usual process of manufacturing transfer points and the like, a certain amount of excess material remains adjacent the back or base wall of the groove, which, although undesirable because of the extra tension it creates in the loops engaged thereby, is, however, not removed because of the complicated machining process which such removal would necessitate. This excess of metal exists in the region where 10 the outer walls of the groove join the curved surface forming the back wall of the transfer point.

15 Although the existence of the aforementioned undesirable qualities are a matter of common knowledge, no method has heretofore been developed to eliminate them which would not sacrifice certain desirable features necessarily associated therewith.

20 One object of this invention is to produce novel wire formed implements of the general type above 25 noted.

25 Another object of the invention is to provide a novel wire formed implement wherein a decrease in the weight thereof has been effected without affecting the requisite degree of balance between 30 the flexibility and rigidity necessarily present therein.

35 A further object of the invention is to provide a novel wire formed implement wherein the wastage of material ordinarily associated with the manufacture of wire-derivative elements, has been substantially decreased or entirely eliminated.

40 The construction of a wire-derivative element and the process of manufacture thereof, according to the principles of the present invention will be fully disclosed hereinafter, reference being had to the accompanying drawing, of which:

45 Fig. 1 is a front elevational view of a transfer point blank with the ends pointed in the desired form;

Fig. 2 is a view similar to Fig. 1 showing the blank following the first grooving operation;

Fig. 3 is a progression of Fig. 2 illustrative of the needle-engaging groove in its finished form;

50 Fig. 4 is a further progression particularly illustrative of the novel construction of the shank of an implement produced in accordance with the principles of the present invention;

55 Fig. 5 is an enlarged side elevation of a finished

transfer point with portions thereof broken away;

Fig. 6 is an enlarged transverse sectional view taken on line 6—6, Fig. 2;

Fig. 7 illustrates a progression of Fig. 6 taken 5 on line 7—7, Fig. 3;

Fig. 8 shows a transverse sectional view of the shank of the transfer point taken on line 8—8, Fig. 4; and

Fig. 9 is a side elevation of a narrowing point 10 embodying my novel construction.

In accordance with the present invention, a novel method of production is employed which, while it substantially eliminates the previously enumerated undesirable features ordinarily associated with and attending the manufacture of 15 loop transfer points, and without surrendering any of the requisite flexibility or strength thereof, permits the use of a base wire having a diameter which is approximately ten per cent. smaller than 20 that of the wire ordinarily used for producing a point of the same given gauge, thereby eliminating the waste ordinarily created by the reducing process of the prior art, by modifying the cross-sectional form of the shank or stem structure in 25 a manner which will provide an implement having a shank which will be equally as rigid and flexible as the usual cylindrical shank, while using approximately ten per cent. less material.

After the base wire has been straightened and 30 cut to desired lengths, the ends of each length or section 10 are shaped to conform with the blank shown in Fig. 1, the one bluntly pointed end 11, hereinafter referred to as the butt end, being so shaped to facilitate the insertion thereof into one 35 of the openings provided in a transfer bar or other holder, whereas the opposite end is formed into a gradually tapered relatively sharp point 12, to permit ready engagement thereof with a cooperating needle.

40 During a subsequent swaging or pressing operation a groove 13a is roughly formed in the lower or body portion 15 of the transfer point blank, to produce the cross-sectional form or outline shown in Figs. 2 and 6. It will here be observed that the 45 depth of the groove 13a of Fig. 6 is appreciably less than that of the finished groove 13 shown in Fig. 7; likewise, the walls 14a, 14a of Fig. 6 are correspondingly heavier than the walls 14, 14, shown in Fig. 7.

50 In order to decrease the thickness of the walls 14a, 14a of Fig. 6 to the dimensions shown at 14, 14 in Fig. 7 and to increase the depth of the groove 13a, in Fig. 6 to that shown at 13 in Fig. 7, a second pressing operation is employed which narrows 55 and deepens the groove, to the size and shape shown in Figs. 3 and 7. During this pressing process, the walls 14a, 14a are thinned out by an upsetting of the metal of the said walls, wherein the metal forced out thereby flows toward the 60 free edges of the walls of the grooved body 15, to increase the height of the walls 14a, 14a of the groove 13a to the proportions shown in Fig. 7, consequently increasing the depth of the groove 13a to the desired dimensions, said reduction of the 65 thickness of the walls being effected without wasting material.

Because of the smaller size of wire used, as compared to the usual procedure, the curvature of the back of the body portion 15 is such as to make 70 the outer sides of the walls 14, 14 disposed tangentially thereto and in this way the excess metal ordinarily existing in that area is entirely eliminated, which in turn substantially reduces the stretch or tension in the loops engaged thereby, 75 the degree of tension being directly proportional

to the cross-sectional dimensions of the body 15 of the finished transfer point.

Although the wire used in forming a transfer point in accordance with the present invention, is approximately ten per cent. smaller in diameter 5 than the wire ordinarily used, and ten per cent. smaller than the required cross-sectional dimension of the shank of the finished transfer point, a shank portion possessing strength and flexibility equal to those characteristics of the transfer 10 points of the prior art is provided. The outer cross-sectional dimensions of the shank of a transfer point made according to the present invention is of a size sufficient to permit the same to be interchangeably supported in the usual transfer 15 bar or other point holder in the same sturdy manner as that characterized by the prior art common type of transfer point.

In order to provide a shank possessing the above 20 noted essential features, the shank portion 16a of the partially completed transfer point shown in Fig. 3 is subjected to a pressing or swaging operation during which the cross-sectional form thereof is transferred from the circular section shown in dots in Figs. 6 and 7 to the cruciform or fluted form shown at 16 shown in Fig. 8.

During the fluting operation, pressure is applied to circumferentially spaced longitudinally extending portions of the shank 16a until the metal thereof flows, whereby grooves 17 are 30 formed as shown in Figs. 4 and 8, the flow of metal passing into the intermediate pressure free areas which cause these areas to expand or bulge into the raised portions or protuberances 18, whose outer surfaces constitute disconnected arcs 35 of a circumference defining a common diameter, the dimension of which coincides with the diameter of a prior art transfer point of the usual gauge specifications.

The protuberances 18 are so spaced about the 40 periphery of the shank 16 as to be in line with the usual points where the shank of a transfer point is contacted by the body of the transfer bar and by the retaining clamp element. The ribs 18, 18 are also disposed in position to impart the requisite desired degree of rigidity to said points, i. e. in line with the needle grooves, since the tendency of the transfer point to flex 45 as a result of the pressing action created between the transfer points and the coating 50 needles is exerted against the base of the groove in a plane extending longitudinally of and laterally bisecting the groove and the shank through oppositely disposed ribs 18, 18, while the lateral tension of the loops tends to flex the 55 transfer points in a plane at right angles to the aforesaid action which is resisted by the second oppositely disposed pair of ribs 18, 18 lying in a plane at right angles to the plane which bisects the first said oppositely disposed pair of ribs.

60 From the above, it will be obvious that a novel structure having a cruciform, fluted, or corrugated cross-section is provided, which embodies a degree of rigidity in its ribwise directions which is equivalent to that heretofore obtainable only 65 when using a shank containing at least ten per cent. more metal than used in forming the novel shank structure 16. An appreciable saving in material is thereby obtained without surrendering any of the desirable features characteristic 70 of and necessarily associated with the usual transfer point.

75 During a following operation the butt end 11 is bent to form the foot or crank 20 and the point 12 is bent in the desired manner to effect the fin-

ished point shown in Fig. 5, the crank 20 being so formed in order to coact with openings in the holder and thereby definitely locate the separate transfer points in correct alignment with each other, whereas the point 12 is shaped to permit ready engagement with the grooves of the members coacting therewith.

The body 15 and shank 16 of the transfer point shown in Fig. 5 are broken out to illustrate that either part may be shortened or lengthened in order to produce an implement of the desired proportions. In accordance with this idea, Fig. 9 is illustrative of another form of point member, being of the type commonly used to effect narrow or lace stitches in the production of full fashioned hosiery, in which the present invention may likewise be profitably incorporated. In the point shown in Fig. 9, it will be observed that the stem or shaft 16 is lengthened and the body or loop-engaging element 15 is shortened, as compared with the transfer point heretofore described, likewise the butt 20 and point 12 extend in opposite directions relative to each other instead of in the same direction, as in the case of the transfer point shown in Fig. 5.

It will thus be observed that through the medium of the present invention, a novel structure and method for producing wire-base implements is provided which effects an appreciable saving in both time and labor over and above the usual manufacturing process without diminishing or surrendering any of the essential features necessarily embodied therein.

I claim:

- 35 1. A wire-base knitting implement comprising a fluted shank having an actual diameter greater than the original diameter of the base wire.
- 40 2. A wire-base knitting implement comprising a fluted shank, the ribs of the fluted shank being disposed in pairs diametrically opposite each other and having an actually effective diameter greater than the original diameter of the base wire.
- 45 3. A wire-base implement comprising a fluted shank having an effective diameter greater than the normal diameter of the base wire, and a grooved portion coextensive with the fluted shank and comprising a substantially V-shaped cross-section including divergent side walls connected by an arcuate back wall with its maximum radius substantially equal to the normal maximum radius of the wire and substantially tangent to the outer surfaces of said side walls.
- 50 4. A wire-base implement comprising a fluted shank having an effective diameter greater than the normal diameter of the base wire, the ribs of the fluted shank being disposed in diametrically opposite relation, a grooved portion coextensive with the fluted shank and comprising a substan-

tially V-shaped cross-section including divergent side walls connected by an arcuate back wall with its maximum radius substantially equal to the normal maximum radius of the wire and substantially tangent to the outer surfaces of said side walls, the groove of said grooved portion being disposed in substantially longitudinal alignment with one of said ribs.

5 5. A wire-base implement comprising a fluted shank having an effective diameter greater than the normal diameter of the base wire, a grooved portion coextensive with the fluted shank having a cross section of substantially V-shape providing divergent side walls connected by an arcuate back wall with its maximum radius substantially equal to the normal maximum radius of the wire and substantially tangent to the outer surfaces of said side walls, said groove being disposed in substantially longitudinal alignment with one of said ribs, and a butt extending at an angle to and composed of, a portion of the fluted shank.

10 6. A wire-base implement comprising a fluted shank having an effective diameter greater than the normal diameter of the base wire, and a grooved portion coextensive with the fluted shank of substantially V-shape in cross-section including divergent side walls connected by an arcuate back wall with its maximum radius substantially equal to the normal maximum radius of the wire and substantially tangent to the outer surfaces of said side walls, the groove of said grooved portion being disposed in substantially longitudinal alignment with one of the said ribs of said fluted shank, and a butt composed of a portion of the fluted shank and extending at an angle to the axis of the shank in a plane substantially bisecting the longitudinally aligned rib and groove longitudinally thereof.

15 7. A wire-base knitting implement comprising a fluted shank and a body portion of substantially channel shape, said shank having an actual diameter greater than the original diameter of the base wire.

20 8. A wire-base knitting implement comprising a shank having one or more depressions therein, and a substantially V-shaped body portion, said shank having an actual diameter greater than the original diameter of the base wire, and a portion of said shank extending at an angle to the remainder of the shank constituting a butt for said implement.

25 9. A wire-base knitting implement comprising a shank provided with one or more longitudinal depressions therein, and having an actual effective diameter greater than the original diameter of the base wire.

FRIEDRICH MAX CLAUSS.
